LOOM BUNTER

Original Filed April 8, 1924 3 Sheets-Sheet 3

UNITED STATES PATENT OFFICE.

ADOLPHUS HENRY LANDRY, OF TOWNSEND, MASSACHUSETTS.

LOOM BUNTER.

Application filed April 8, 1924, Serial No. 705,149. Renewed November 11, 1925.

To all whom it may concern:

Be it known that I, ADOLPHUS H. LANDRY, a citizen of the United States, and a resident of Townsend, in the county of Middlesex 5 and State of Massachusetts, have invented a new and Improved Loom Bunter, of which the following is a full, clear, and exact description.

This invention relates to improvements in 10 loom bunters, an object of the invention being to provide a bunter which may be used in connection with any ordinary stop motion and which will function positively to stop the loom on a quarter of a pick or a 15 quarter of a turn of the lay, which insures a practically instantaneous stop when the filler thread breaks.

With bunters such as heretofore employed on looms in connection with stop motions, 20 the loom is permitted to run over one additional pick at least before being brought to a full stop. This seriously interferes with the quick resetting of the loom and slows up the action to a material extent, not 25 to mention the fact that there is a wastage of thread or yarn and more or less imperfect operation.

It is the purpose of my invention to provide a bunter which stops the loom as soon 30 as the break occurs, thus permitting a quick repair and quick return to operation. This is an economy of material and time and is an extremely important item in the trade where competition is so keen.

35 A further object is to provide a bunter of extremely simple construction which will most efficiently perform the functions for which it is intended.

With these and other objects in view, the 40 invention consists in certain novel features of construction and combinations and arrangements of parts which will be more fully hereinafter described and pointed out in the claims.

45 In the accompanying drawings—

Figure 1 is a view in front elevation illustrating such portions of a loom as are necessary to indicate the operation of my improved bunter;

50 Figure 2 is a view in section on the line 2—2 of Figure 1, showing the normal position of the co-operating parts;

Figure 3 is a view in section on the line 3—3 of Figure 1, showing the normal posi-

tion of parts and illustrating in detail my 55 improved bunter, which is supported just under the breast beam of the loom;

Figures 4 and 5 are views similar to Figures 2 and 3 but showing the position of parts after a filler thread breaks and illustrating my improved bunter in operative position to stop the loom;

Figure 6 is a fragmentary plan view illustrating the position of the dagger and its co-operating parts.

1 represents the frame of the loom which is provided with an ordinary breast beam 2 and lay 3. The lay 3 is provided with a feeler wire 4 normally held in elevated position by the filler thread carried by the shuttle 5. This feeler wire is operatively connected by a link 6 with a dagger 7 pivotally connected to the lay and movable over a fixed bracket arm 8 on the breast beam 2. 70 9 represents a pivoted dog which is provided with a pin 10 engaging an arm 11 fixed to the shipper shaft 12, and 13 is the ordinary shipper handle fixed to this shaft for manually moving the same to release a clutch 14 and stop the loom.

The parts above described are standard equipment and constitute one form of stop motion, and I would have it distinctly understood that while I illustrate my invention in connection with this particular stop motion it is not limited in such respect as it may be used in connection with various other stop motions.

My invention consists in the provision of a pivoted bunter arm 15 which is pivotally connected at its lower end, as shown at 16, to the loom frame 1 and at its upper end is perforated to receive a plunger rod 17 mounted in a bracket 18 on the frame 1. A coil spring 19 is provided on the rod 17 between the bracket 18 and the arm 15, and heads or enlargements 20 and 21 are formed on the respective ends of the rod 17 to hold the assemblage in proper relation, as clearly indicated in Figures 3 and 5.

The arm 15 is normally in the position shown in Figure 3 and held in this position by the spring 19. The arm 15 carries a pivoted dog 22 having a shoulder 23 thereon against which the lay 3 engages when the bunter is in operation. This dog 22 normally hangs in an inoperative position, as shown in Figure 3, and is engaged and moved up

wardly by a crank arm 24 on a shaft 25, which latter is supported in the loom frame 1 parallel to the shipper shaft 12. Fingers 26 and 27 are secured to the shafts 25 and 12, respectively, so that when the shipper shaft 12 is turned in one direction the finger 27 will cause the finger 26 to move and bring the bunter mechanism into operative position and function with the stop motion to bring the loom to a quick stop.

The broad purpose of my invention is, however, to automatically apply the bunter and this is accomplished by reason of the fact that an arm 11 turns freely on the shipper shaft 12 and is provided with a finger 28 engaging a finger 29 on the shaft 25, as will be hereinafter explained.

Referring to Figures 3 and 5, it will be noted that an elastic cushion 30 is provided on the loom frame in the path of movement of the arm 15 so as to limit the movement of this arm 15 in one direction.

Figure 2 illustrates in full lines the normal extreme movements of the lay. When, however, the filler thread on the lay breaks, the feeler wire 4 drops to permit the dagger 7 to move downwardly a distance sufficient to strike the dog 9, and when this occurs the dog 9 moves the arm 11 and fingers 28 and 29 to impart a partial turning movement to shaft 25. This movement of shaft 25 through the medium of the arm 24 elevates the dog 22 into the path of the lay 3. When the lay 3 strikes the shoulder 23 of dog 22 it receives the action of the bunter as this movement of the lay forces the arm 15 in a direction against the tension of spring 19, the extreme movement in this direction being indicated in Figure 5. The spring 19 throws the lay back to its normal position but has checked the momentum of the lay and brought the same to a stop almost instantaneously with the functioning of the stop motion. It is, of course, to be understood that the stop motion functions when the filler thread breaks as the throwing off

movement of the dog 9 functions to release the stop motion.

I have purposely refrained from illustrating any portion of the loom other than is necessary to point out the operation of my improved bunter, and I do not wish to be limited in any respect to a loom structure or a stop motion of any particular design or construction but wish to cover broadly my improved bunter which functions to stop the loom practically instantaneously upon the breaking of a filler thread.

Various slight changes and alterations might be made in the general form of the parts described without departing from my invention, and hence I do not limit myself to the precise details set forth but consider myself at liberty to make such slight changes and alterations as fairly fall within the spirit and scope of the appended claims.

I claim:

1. A bunter mechanism for looms, comprising a pivoted arm, a spring-pressed bolt engaging the arm, a cushion limiting the movement of the arm, a pivoted dog on the arm, and means for moving the dog into the path of the lay whereby the spring-pressed arm functions as a bunter to stop the lay.

2. In a loom the combination of a frame, a lay pivotally connected to the frame, a shipper shaft in the frame, a handle on the shipper shaft, a clutch controlled by the shipper shaft, a pivoted dog, an arm loosely mounted on the shipper shaft and controlled by the dog, a second shaft parallel to the shipper shaft, fingers on said shaft compelling their simultaneous turning movement, an arm on the last-mentioned shaft, a bunter mechanism moved into operative position by said last-mentioned arm and adapted to stop the lay, and a pivoted dagger on the lay adapted when a filler thread breaks to engage the dog and cause the brake to assume an operative position.

ADOLPHUS HENRY LANDRY.
